UNITED STATES PATENT OFFICE.

ERNEST AARON PETERSON, OF OAKLAND, CALIFORNIA.

CASEMENT SASH.

Application filed November 10, 1923. Serial No. 673,926.

My invention is an improved casement sash.

The object of my invention is to provide a casement sash which may be secured in any 5 desired open position.

Another object is to provide roller mountings for the sash, which will not sag in use.

A further object is to provide yieldable members at the sides of the frame to exclude 10 rain and wind.

In the annexed drawing in which my invention is illustrated:

Figure 1 is a perspective view of my window in an open position.

15 Figure 2 is a sectional view taken on the line 2—2 of Figure 1.

Figure 3 is a sectional view taken on the line 3—3 of Figure 1.

20 Figure 4 is a side view of the top sash supporting roller.

Figure 5 is a plan view of the bottom sash supporting roller.

Referring more particularly to the drawing: the sash 1 is mounted in a frame 2, by 25 means of upper roller member 3, and lower roller member 4. The member 3 comprises a roller frame 5 in which a pair of rollers 6 and 7 are journaled, and a rod 8 depends from the frame into a bore 9 in the sash 1.

30 A nut 10 is positioned in the bore 9 and the rod 8 is threaded into it. The bore 9 extends out of the sash 1 at an angle so that a tool can engage the rod 8 by means of a slot at its lower end to adjust the rollers as 35 will be further described.

The roller frame 5 and rollers 6 and 7 travel in a transverse groove 11 in the window frame 2 and the rod 8 extends through a slot 12 in the window frame into the sash, 40 as shown in Figure 3. When the sash is hung in the window frame the rod 8 is adjusted in the nut 10 until the sash swings properly.

The lower roller member 4 comprises a 45 horizontal roller frame 13 upon which are mounted rollers 14 and 15. These rollers are adapted to travel in a groove 16 in the sill 17 of the frame 2. The groove is the proper width so that the rollers 14 and 15 engage both sides of the groove thus eliminating any transverse motion in the frame 13 and the sash 1. The frame 13 is pivoted 50 to the sash 1 by a pin 18, which pin has a head 19 bearing against the sill 17. A suitable spring fastening means 20 engages 55 the pin 18 to hold the sash in any desired

position. A groove 21 is formed in the frame 13, into which a plate 22 is adapted to fit. This plate is secured to the sill 17 and extends the width thereof. The object 60 of this construction is to prevent rain from entering the groove 16 and rusting the rollers 14 and 15.

To prevent rain, dust, etc. from entering at the sides of the sash, I have provided 65 yieldable vertical weather strips 23 at the sides of the frame 2. The strip is hinged at 24 in a recess 25 in the frame 2. A spring 26 urges the strip 23 outwardly and a stop screw 27 limits its outward movement. The outer edge of the strip 23 is enlarged as at 28 and the sash is adapted to rest back of said enlargement thus effectively sealing it against rain and dust.

When the sash is closed, it engages the 75 strip—depresses it against the tension of the spring 26—until it reaches its normal closed position when the spring forces the strip outwardly and seals the window.

Arms 29 and 30 are pivoted to the sash 80 and frame at the top and bottom thereof respectively, to support and pivot the sash.

Having described my invention I claim:

1. In a casement sash, a frame, a sash having a bore extending from the upper 85 edge to the side edge thereof, a nut secured to said sash, and extending within said bore, a roller member consisting of a roller frame, rollers carried by said roller frame and adapted to travel within a groove within the window frame, a rod extending below said frame and secured to said nut, said rod having a slot within its lower end whereby the rod may be adjusted by means of a suitable tool inserted from the lower end of 90 said bore.

2. In combination a window frame, a sash therefor, said frame having a groove therein, a roller member consisting of a roller frame, rollers carried by said roller frame and adapted to extend within said groove, a pivot pin for said roller member, a head carried by said pin and means to cause said head to be pressed against said window frame at any desired point.

3. In combination a window frame, a sash therefor, said sash being provided with an opening therein, said frame being provided with a groove, a roller member consisting of a horizontal frame, rollers carried by said horizontal frame, a pin carried by said sash and serving as a pivot for said roller mem-

ber and means whereby said pin may be forced into contact with said window frame at any desired point.

4. In combination a window frame provided with a groove in the sill portion thereof, a plate secured to said sill and provided with a flange, a roller member, rollers carried by said member and adapted to extend within said groove, said member having a groove therein adapted to receive said flange whereby rain may be prevented from entering said groove.

5. In combination, window frame, a sash having a bore extending from the upper

edge to the side edge thereof, a nut positioned within said sash and extending within said bore, a roller frame carrying a plurality of rollers, said roller frame and rollers being adapted to travel within a groove within the window frame, a rod depending from said roller frame and engaging said nut, said rod being provided with means whereby it may be adjusted relative to said nut.

In testimony whereof I affix my signature.

ERNEST AARON PETERSON.
